UNITED STATES PATENT OFFICE.

WILLIAM H. SMOCK, OF NEW YORK, N. Y.

DESIGN FOR A CUFF.

SPECIFICATION forming part of Design No. 24,870, dated November 12, 1895.

Application filed August 22, 1895. Serial No. 560,170. Term of patent 14 years.

To all whom it may concern:

Be it known that I, WILLIAM H. SMOCK, a citizen of the United States, and a resident of New York, in the county of New York and State of New York, have invented and produced a new and original Design for Cuffs, of which the following is a specification.

Reference is to be had to the accompanying drawings, which form a part of this specification, and in which like letters of reference indicate corresponding parts in both the figures.

Figure 1 is a plan view showing my newly-designed cuff detached and spread out flat, and Fig. 2 is a plan view showing the same ; rolled with its ends adjacent to each other and its laps lapped one upon the other.

The leading feature of my design consists in four semiscallops or quadrants, the outer angles of which join straight parallel margins of the body of the cuff, while the inner adjacent, angles thereof join separate straight lines, which are intermediate of and parallel

with the said straight marginal lines of the body.

A represents the body of the cuff, showing 25 straight marginal edges, which constitute the edges of the cuff. The ends B B thereof each show two semiscallops or quadrants a a, the outer angles of which join straight and opposite marginal edges, while the inner adjacent angles of said semiscallops or quadrants 30 join an intermediate straight marginal edge, as by the edges of a projection b, which said edges are parallel or approximately parallel with the main marginal edges of the body A. 35 The said inner angles are joined as by lines c or c'.

What I claim is—

The design for a cuff, substantially as shown and described.

WM. H. SMOCK.
